UNITED STATES PATENT OFFICE.

GEORGE H. LELAND AND ROBERT H. AHLERS, OF DAYTON, OHIO, ASSIGNORS TO THE DAYTON ENGINEERING LABORATORIES COMPANY, OF DAYTON, OHIO, A CORPORATION OF OHIO.

DEVICE AND METHOD FOR ASSEMBLING ARMATURES.

Application filed May 17, 1920. Serial No. 382,089.

To all whom it may concern:

Be it known that we, GEORGE H. LELAND and ROBERT H. AHLERS, citizens of the United States of America, residing at Dayton, county of Montgomery and State of Ohio, have invented certain new and useful Improvements in Devices and Methods for Assembling Armatures, of which the following is a full, clear, and exact description.

10 This invention relates to the manufacture of armatures and more particularly to the art of securing a plurality of wires in the open slot of an armature core.

15 The principal objects of the present invention are to provide a method and apparatus for inserting micarta, paper, or other strips in the opening in an armature slot to hold a plurality of wires in the latter whereby the cost of manufacturing the cores is reduced 20 and greater uniformity in the product is secured.

25 Further objects and advantages of the present invention will be apparent from the following description, reference being had to the accompanying drawing, wherein a preferred embodiment of the present invention is clearly shown.

Referring to the drawings:

Fig. 1 is a perspective view of the device 30 used in assembling armatures;

Fig. 2 is a perspective view of a retainer strip to be inserted in the armature slots by the device shown in Fig. 1;

35 Fig. 3 is a perspective view of a removable magazine container forming a part of the device;

Fig. 4 is a plan view of the device shown in Fig. 1;

40 Fig. 5 is a side elevation of the device shown in Fig. 1;

Fig. 6 is a sectional view taken along the line 6—6 of Fig. 4;

45 Fig. 7 is a view similar to Fig. 5, the parts being shown in their respective positions immediately after the operation of inserting the retainer strip in the armature slot has been completed;

Fig. 8 is an enlarged front view of the device;

50 Fig. 9 is a view showing the device entering the armature slot, a portion of the device being shown in elevation while a portion of the armature core including one slot is shown in section. This view illustrates

the device forcing the armature windings 55 down into the core and having its knife inserted between the periphery of the core and the surrounding insulating lining material;

Fig. 10 is a view similar to Fig. 9, the device, however, being shown in part section 60 taken along the line 10—10 in Fig. 7 and illustrates the step of folding the cut edges of the insulating lining material against the windings in the slot;

Fig. 11 is a fragmentary sectional view of 65 a portion of the armature core showing the retainer strip inserted in the armature slot between the turned down edges of the insulating material and the restricted edges of said slot; 70

Fig. 12 is a side elevation view showing the device being forced into the armature slot by means of a power controlled hook, a part of the armature being broken away. The device is shown in a position where the 75 forcing down operation, cutting operation and folding operation have been in progress and the strip inserting operation about to start;

Fig. 13 is a view similar to Fig. 12 and 80 shows the position of the different elements at the completion of the operations;

Fig. 14 is a sectional view taken on the line 14—14 of Fig. 12;

Fig. 15 is a side view of a modified form of 85 the device; and

Fig. 16 is a side elevational view partly in section of the device shown in Fig. 15, the device being in extended position in Fig. 16. 90

In assembling armatures, it has been the practice, after the laminations of the core have been secured to the armature shaft, to face the core teeth and to line the core slots with a continuous strip of insulating material which covers the interior surfaces 95 of the slots and the periphery of the core. Then the windings are inserted in their respective slots. The operator then forces the windings down into the slots as far as possible, after which he cuts the insulating lining material at the edges of the slots and periphery of the core. The compacting of the windings is usually effected by hammering on a bar projecting through the slot opening and resting on the windings. These 100 two last mentioned operations require separate tools. Following these operations the sheared edges of the insulating lining are 105

turned down against the windings in the slots. The next operation completes the assembling of the armature by inserting a retainer strip, which in the form shown 5 consists of stiff insulating material, in the slots on top of the turned down edges of the lining material, for preventing the windings flying out, due to centrifugal force when the armature is in operation.

10 From the foregoing description it can be clearly seen that this method is slow, necessitates a series of operations requiring a separate tool for each operation, and that between the operations of driving the windings together and inserting the retaining strip the windings loosen and increase the difficulty of inserting the strip.

15 Referring more particularly to the Figs. 1, 4, 5, 6 and 7, the device is shown comprising a relatively movable portion which may be termed the "pilot member" and a relatively stationary portion which may be termed the "housing member."

20 In order to simplify the description and thus permit a clearer understanding of the construction of the device, the pilot member will first be fully described.

25 The pilot member is designated by the numeral 20 and comprises a guide portion 21, provided with web and flange portions, 22 and 23 respectively. At the forward extremity, the guide, web and flange portions 21, 22 and 23, are rounded off in order to facilitate their introduction into the slots 30 of the armature as will be fully explained hereinafter. As is shown in Figs. 8 and 9, the under surface of flange portion 23 is concaved for purposes to be set forth.

35 In the web portion 22, and adjacent to the forward extremity thereof, there is provided a transverse slot 24 (see Fig. 6) adapted to receive a knife 25. This knife 25 has two angularly arranged cutting surfaces 26, the apex of the angle between these two cutting 40 surfaces being adapted to abut against the forward end wall of the slot 24. The body portion of the knife 25 is rounded off as at 27 in order to permit the knife to be swung into position in the slot. A vertical 45 set screw 28, is adapted to be screwed into the guide portion 21, of the pilot member 20, the screw being of such length as to permit its lower end to engage with the knife 25 in the slot 24, to securely hold said knife 50 in the desired position. A pin 29 passing transversely through the guide portion 21, and having portions thereof projecting on each side of said guide portion is also held 55 in position by the screw 28 passing therethrough.

60 Another pin 30, is provided in the top of said guide portion 21 and is so located as to act as a stop for certain movable parts explained hereinafter.

65 Adjacent to the slot 24, a notch 31 is pro-

vided which spaces the web 22 and the flange 23 from a web 22^a and a flange 23^a, aligned respectively with web 22 and flange 23. This notch 31 is so formed as to have a face 32 substantially perpendicular to flange 70 23 at its forward side while the opposite face is inclined as at 33 to gather or fold the edges of an insulating paper over the windings. The web portion 22 between the notch 31 and the forward extremity of the 75 guide 21 is of smaller transverse dimensions than the web portion 22^a on the opposite side of said notch. This web portion 22^a is provided with flange portion 23^a for only a part of its length, some of the flange portion 80 being cut away to provide a receptacle for the retainer strip as will be explained later and to permit the withdrawal of the pilot or guide bar radially from the slot.

85 By referring particularly to Fig. 6, the pilot member 20 is shown having an enlarged body portion 34. Adjacent to the pilot member and in said body portion there is provided a chamber 35, adapted to receive the retainer strip magazine 36.

90 A recess 37 is formed in the body portion 34, at each end of the chamber 35. Each of these recesses contains a latch member 38, fulcrumed on the pin 39 and held in normal or locking position by the coil spring 40. 95 These latch members 38 are adapted to hold the retainer strip magazine 36 in position within the chamber 35.

100 Adjacent to the lower forward end of the chamber 35 and adjacent the inner end of the web portion 22^a, there is provided a detent 42, slidably arranged in a recess 41 formed in the body 34. This detent has a cylindrical upper guide portion 105 43, see Fig. 5, and a rectangular lower portion 44. The bottom of this rectangular lower portion 44 is slightly inclined as at 45 for purposes hereinafter described. Where the cylindrical and rectangular portions of the detent 42 conjoin a shoulder 110 is formed which engages with a stop 46 secured to the web portion 22 in any suitable manner to retain the detent in the recess 41. A coil spring 41^a tends to normally hold the detent in a depressed position to 115 engage a retaining strip carried by the housing member.

120 The body portion 34 is provided with a slot 47, and a pin 48 extends across slot 47 and is attached to one end of a spring 49 (Fig. 6).

125 Holes 50, are provided to reduce the weight of the body 34.

Body 34 has a reduced shank portion 51 on which is mounted handle 52 secured thereto by means of the screw 53.

130 Referring to Figs. 3 and 6, the retainer strip magazine 36 comprises a receptacle 53 which is adapted to hold a plurality of retainer strips 54 made of any suitable,

insulating material. A cover plate is secured to the receptacle 53 and is adapted to be engaged by latches 38 to hold the magazine 36 in position in the chamber 5 35. Passing through this cover plate is a rod 55, having a knob 56 secured to its outer end, while the inner end of said rod 55 carries a plate 57 which is adapted to press against the stack of retainer strips 10 54. The rod 55 is provided with a notch 58 with which the latch 59, slidably secured to the cover plate of the magazine 36, is adapted to engage, to hold the plate 57 in a position near the said cover plate to 15 facilitate the loading of said magazine with retainer strips. A pair of oppositely disposed spring blades 60 tend to force the plate 57 and consequently the stack of retainer strips downwardly in the magazine 20 as shown in Figs. 3 and 6.

In Fig. 6, the guide portion 21 of the pilot 20 may be made up of two separate pieces 21 and 21^a, held together by means of a series of screws 21^b. The main object of 25 this method of construction is to eliminate the necessity of discarding the entire piece if for any reason the guide member 21 or its associated parts are damaged during the use of the device. Due to abnormal strains 30 these parts may be damaged and if so, the construction illustrated in Fig. 6 will permit replacing the portion 21^a thus making the entire device again usable.

The stationary element associated with 35 the heretofore described elements will not be described.

By referring to the Figs. 1, 4, 5, 6, 7 and 8, the numeral 75 designates the relatively stationary element of the device, 40 which will be termed the housing. This housing consists of two side walls 76 and 77, and upper and lower plates 78 and 79 respectively. The plate 78, securing the two side walls together at their upper edges, 45 is cut away to permit the removal of the retainer strip magazine 36 without disassembling any portion of the device. The plate 78 engages with the upper surface of the body portion 34 thus forming a bearing 50 for this body portion. A channel 78^b is formed in the under surface of plate 78 in order to provide a clearance over the cover plate of the magazine 36 when the device is in operation.

55 In order to provide an upper bearing at the forward extremity of the side walls 76 and 77, a plate 82 is provided, said plate being secured to the edges of both or formed integral with one and secured to the other 60 upper edge of either of the said side walls 76 and 77. This plate 82 is channelled as at 83 to fit the contour of the guide portion 21 of the pilot 20.

As has been mentioned heretofore, the 65 housing 75 is provided with a bottom or

lower plate 79 secured to the lower edges of the side walls 76 and 77, said lower plate being of such length, that its forward edge 80 comes into close proximity to the inclined side of the rectangular portion 44 of detent 70 42, when the movable element of the device is shifted to the extreme right hand portion relative to the housing 75 as is shown in Fig. 7. A longitudinal channel 81 is formed in the inner surface of the plate 79 and 75 extends from the forward edge 80 of said plate 79 rearwardly to a line 81^a where the channel is narrowed and thence rearwardly to a line 81^b which is slightly beyond the point where the detent 42 is located relative to the housing 75 when the different parts of the device are in the positions shown in Fig. 6. The channel 81 is of 80 slightly greater transverse dimension than the web portion 23, the depth of said channel being substantially equal to the thickness of a retainer strip 54. From line 81^a to line 81^b, the channel 81 is less in width than retainer strip 54, but greater in width than detent 42 (Fig. 14) to permit the detent to drop into the channel at a point in back of the retainer strip.

By forming the channel 81 wider than the web 23, a relatively wide retainer strip may be employed which may be wedged tightly 95 into the armature slot in the space provided by the progressive wedging of the windings away from the under cut shoulders at the neck of the slot.

Both side walls 76 and 77 are provided 100 with ears 82 oppositely disposed. These ears are so positioned that a screw 83 passing through both, is adapted to pass through the slot 47 also. This screw is held in position in the ears by means of a nut 84, said screw acting as anchorage for one end of the spring 49, the other end of which is anchored to a pin 48 carried by the body 34.

Having described the construction of the 110 device and its component parts, the mode of operation of the same will now be set forth.

The retainer strip magazine 36 is first 115 filled, after removing same from the chamber 35 in body portion 34. The magazine can be removed by depressing the latch members 38. As the springs 60 normally tend to push the plate 57 out of the receptacle 53, the said plate may be drawn into the said receptacle by means of the rod 55 to provide 120 space for the stack of retainer strips to be inserted. In order to facilitate this loading or inserting of the retainer strip pack, a sliding catch 59 is brought into engagement with the groove 58 formed in rod 55. Rod 55 will be held in this loading position, 125 thereby preventing the springs 60 from forcing the stack of retainer strips out of the receptacle 53 during the loading operation. After loading, the magazine 36 is placed 130 within the chamber 35 in which position the

latches 38 will firmly hold it. Then the catch 59 is withdrawn from engagement with the slot 58, permitting the springs 60 to push the plate 57 against the stack of retainer strips and the lower strip against the inner surface of the lower plate 79 of housing 75.

An armature core 90 is provided with a non-conducting wrapping 94 which usually 10 covers its periphery and lines the armature slots. Windings 95 are located in the slots in any suitable manner.

The operator now inserts the nose of the pilot 20 in one of the armature slots, so that 15 the flange portion 23 thereof enters the wire retaining portion 91 of the slot and the web portion 22 enters the restricted neck portion 92 see Fig. 9. Longitudinal pressure is now exerted by the operator, on the 20 handle 52, causing the pilot 20 to further enter the slot, thereby forcing the knife element 25 carried by said pilot, within the space between the lining material 94 and the periphery of the core.

25 Further movement of the pilot in the slot will now cause the angular cutting surfaces 26 of the knife 25 to force the lining material inwardly toward their respective sides of the web portion 22, cutting said lining 30 material at the peripheral edges of the restricted neck 92 of the slot and progressively compacting the winding throughout the length of the slot to provide a space for the leading end of the retainer strip. The pressure, 35 of the web of the pilot against the paper holds the latter stationary during the cutting operation. This web also acts as a guide for the cutting and wedging tools. As shown in Fig. 9, the transverse thickness 40 of the web portion 22 is of such a dimension as to permit it to pass readily between the layers of lining material at the sides of said neck 92. The web portion 22^a at the inclined surface 33, is thicker transversely 45 than the web portion 22 conjoining the perpendicular surface 32, so that when said inclined surface 33 is moved inwardly into the slot, it will engage with the sheared off edges of the lining material in the neck 92, 50 turning them down in such a manner that the following flange 23^a will fold said edges down against the windings in the slot as is clearly shown in Fig. 10. By referring also to Fig. 12, the positions of the various elements of the device relative to the armature, 55 at this stage of the assembly operation, are shown. The lower edge 80 of the housing 75 engages the side wall of the armature to cause a relative movement between the housing and the member 21 and feed a retaining strip into the space provided by the wedging member.

60 As the pilot 20 is moved still further into the armature slot, the flange 23^a will form 65 a pathway between the lining material and

the restricted neck portion 92 of said slot, into which the retainer strip 54 will be inserted. This strip 54 is held in this position by having its forward end, which, as can be seen in Fig. 2 is pointed, fit in a correspondingly shaped cut away portion in the flange 23^a, while its rear end is engaged by the dent 42 and by the edge of channel 81 at line 81^a. The manner in which this retainer strip 54 is held in position relative to the web portion 22^a, substantially causes it to form a continuance of the flange portion 23^a, thereby tending to cause said strip to follow the flange portion 23^a into the space in the armature slot above the cut edge portions of 80 the lining 94 as shown in Fig. 11.

In order that this device may be used for completing the assembly of a series of armature slots without the necessity of manually loading or placing a retainer strip in position preliminary to each operation, there is provided a magazine 36, which as has been set forth in some of the preceding paragraphs, is adapted to carry a supply of retainer strips for a series of operations. It 90 has also been mentioned and is clearly shown in Fig. 6 that the bottom strip in the stack included in the magazine rests upon the inner surface of the lower plate 79 of the housing 75 due to the pressure of the springs 60 on the plate 57 resting on the top of the stack of retainer strips.

Now in order to replace the retainer strip 54, held in position in the receptacle in pilot 20, with a strip from the magazine after the first one has been inserted in the armature slot, the housing 75 is provided with an edge or surface 80, which, as is shown in Figs. 12 and 13 is adapted to engage with the edge of the core of the armature thereby causing 100 relative movement between the pilot and body portion 20, and the housing portion 75 of the device. This relative movement between these elements will cause the lowest retainer strip in the pack included in the 105 magazine to slide along the lower plate 79 until the limit of travel is reached as shown in Figs. 7 and 13, when said lowest retainer strip will be forced down into the channel 81 formed in the forward portion of lower 110 plate 79.

When the position of the assembling device relative to the armature is as shown in Fig. 13, the operation of forcing down the windings into the core, of cutting and folding the core lining, and of inserting the retainer strip will have been completed. Now if the tool be moved upwardly in the direction of arrow 120 in Fig. 13, the retainer strip will remain in the armature core. The edge 80 being free of the armature core, the spring 49 will be released from distended position and will cause the parts of the assembling tool to return to normal position, shown in Figs. 1, 4, 5 and 6. This return 120

- of these elements to normal position will cause a reverse relative movement between said elements from that described thereby causing the detent 42 to ride or slide over the upper surface of the strip 54 in the channel 81. Due to the fact that one end of said strip 54 abuts against the edge 81^a of the channel 81, said strip 54 cannot move backwardly out of the channel 81, but the detent 42 may slide over strip 54 since detent 42 is provided with an inclined face 45 on its rearward side which causes detent 42 to be forced up into the recess 41 against the pressure of spring 41^a.
- From the foregoing description it can be seen that each cycle of operations will tend to insert a retainer strip into the armature slot, while at the same time another retainer strip will be automatically removed from the stack in the magazine and placed in position to be inserted in the next adjacent armature slot during the following cycle of operation.
- As has been described, the operation of the device is brought about by the operator exerting longitudinal pressure on the handle 52. However, in the Figs. 12 and 13 there is shown mechanical means for transmitting power to cause the pilot 20 to enter and pass through the armature slot. This mechanical means includes cylinder 100, utilizing any suitable means of power to actuate a piston (not shown) which is connected with a rod 101. This rod is provided at its outer end with a fulcrum pin 102 to which is anchored a hook element 103 adapted to engage the pin 29 secured to the pilot member 20. A spring 104 carried by the rod 101 is adapted to hold the hook element 103 in engagement with the pin 29. Any suitable control may be utilized to direct pressure on the piston (not shown) in cylinder, whereby the rod 101 may be moved backwardly and forwardly to effect the operation of the assembling device. Obviously the hinged hook 103 may be swung away from the pin 29 to release the tool.
- The armature may be rigidly held in position by means of any suitable device correctly located relative to the power cylinder.
- In the modified form shown in Figs. 15 and 16, the stationary member 75^x corresponding to member 75 of the first form is provided with a hollow handle 130 into which slides a hollow extension 131 of the member 21^x corresponding to member 21 of the first form. Spring 85^x is attached by pin 83^x to handle 130 and by pin 48^x to member 21^x. For convenience in manufacture the part 135 carrying members 38, 39 and 40 is not constructed integrally with member 21^x but is formed as a separate part and secured to member 21^x by screws 136.
- The compacting of the windings in the slots is effected more uniformly and in a shorter time by the progressive pressing of the wires together than has been possible heretofore and the overlapping of the compacting and strip inserting operations effects an easy insertion of the strip without damage to the latter. It has been found that by moving the strip in after the wedging tool it is not necessary to employ a retaining strip of the size and stiffness employed when the strips were hammered in.
- When the power operated mechanism is employed the whole operation may be performed in a small fraction of the time required heretofore in fact it has been found that when a strip is in operative position on the tool the wedging, cutting and strip placing operations may be performed on the smaller armatures such as are employed in gas engine starting and lighting systems in less than a second.
- While the forms of mechanisms herein shown and described constitute preferred forms of embodiments of the invention, it is to be understood that other forms might be adopted, all coming within the scope of the claims which follow.
- What we claim is:
1. The method of inserting a retaining strip in each of a series of longitudinal slots in an armature core, which includes rotating the core to bring a slot to a predetermined position; moving a wire compacting tool longitudinally through a slot in said position to compress wires in the slot, removing the tool from the opposite end of the slot; and placing a retaining strip in each of the slots while the wires are in compact relation.
  2. The method of inserting a retaining strip in each of a series of longitudinal slots in an armature core, which includes intermittently rotating the core to bring the slots successively to a predetermined position; inserting a wedging tool at one end of a slot in said position; moving the tool through the slot by power operated means operating from the opposite end of the slot; and feeding a retaining strip into the recess progressively with the movement of the wedging tool therein.
  3. The method of completing an armature having an open slotted core, which includes lining the slots with insulating material, in applying windings, and compacting said windings in the slots concomitantly with the cutting off of the insulating material lining the slots.
  4. The method of completing an armature having an open slotted core, which comprises lining the slots with insulating material, in applying windings, and compacting said windings in the slots concomitantly with the inserting of a retainer strip between the windings and the edges of the slots.
  5. The method of completing an armature having an open slotted core, which comprises

lining the slots with insulating material, applying windings, and shearing the lining material adjacent the openings in the slots, concomitantly with the turning down of said sheared edges against the windings in said slots.

6. The method of completing an armature having an open slotted core which includes lining the slots with insulating material, applying windings, and shearing the lining material adjacent the edges of the slots, concomitantly with the inserting of a retainer strip in said slots between the windings and the edges of the slots.

10 7. The method of completing an armature having an open slotted core which includes lining the slots with insulating material, applying windings, and forcing said windings together in the slots concomitantly with the shearing of the lining material at the edges of the slots, while at the same time turning said sheared edges down against the windings in the slots.

15 8. The method of completing an armature having an open slotted core which includes lining the slots with insulating material, applying windings, and forcing said windings together in the slots concomitantly with the shearing of the lining material at the edges of the slots, while at the same time inserting retainer strips into the slots between the windings and the edges of the slots.

20 9. The method of completing an armature having an open slotted core which includes lining the slots with insulating material, applying windings, while concomitantly compacting said windings in the slots, shearing the lining material at the edges of the slots, turning said sheared edges of the lining material down against the windings and inserting a retainer strip into the slots between the windings, and the edges of said slots.

25 10. The method of completing an armature having an open slotted core which includes lining the slots with insulating material, applying windings while concomitantly shearing the lining material at the edges of the slots, and turning said sheared edges of the lining material down against the windings, and inserting a retainer strip into the slots between the windings and the edges of said slots.

30 11. The method of completing an armature having an open slotted core which includes lining the slots with insulating material, applying windings, and turning the edges of the lining material down against the windings concomitantly with the inserting of a retainer strip into the slots between the turned down edges of the lining material and the edges of the slots.

35 12. In an apparatus for compacting a plurality of flexible members in an armature recess formed in part by an undercut shoulder, the combination of a wedging member

adapted to bear at its opposite sides against the undercut shoulder and the flexible members; and means for feeding the wedging member into the recess.

40 13. An apparatus of the class described comprising means for compacting a plurality of wires in an armature recess; and means movable therewith for inserting the leading end of a retaining member into the recess over the compacted wires.

45 14. An apparatus for securing a plurality of flexible members in a bottle shaped armature recess and comprising means movable longitudinally through the recess for pressing the wires away from the neck of the recess; and means for feeding a retaining member into the recess progressively with the pressing of the wires.

50 15. In a tool the combination of a member adapted to be moved longitudinally in a recess in an armature and to be guided by the walls thereof; and a cutting tool guided by said member for cutting insulating material adjacent the opening into the armature recess.

55 16. An apparatus for securing wires in an armature slot and comprising means for inserting a retaining strip in an armature slot; and means for supplying retaining strips to said first named means.

60 17. An apparatus comprising mechanism movable longitudinally in an armature slot to compress wires therein to form a space for receiving a retaining member; means for inserting a retaining member in said space; and means for supplying the retaining members to said last named means.

65 18. An apparatus comprising means for progressively cutting insulating material adjacent the mouth of an armature slot; and means for progressively pressing the severed end portions of the said material onto a plurality of wires in the slot.

70 19. In a device for assembling armatures having an open slotted core lined with insulating material and supporting windings, the combination with a guide element to be inserted in the slots and adapted to compact the windings in the slots; of means guided by said guide element for shearing the lining material adjacent the openings in said slots.

75 20. In a device for assembling armatures having an open slotted core lined with insulating material and supporting windings, the combination with a guide element to be inserted in the slots and adapted to compact the windings in the slots; of means guided by said guide element for inserting a retainer strip in the slots between the windings and the edges of said slots.

80 21. In a device for assembling armatures having an open slotted core lined with insulating material and supporting windings, the combination with a guide element to

- be inserted in the slots; of means guided by said guide element for cutting the lining material at the edges of said slots; and means guided by said guide element for turning the sheared edges of the lining material down against the windings in the slots.
22. In a device for assembling armatures having an open slotted core lined with insulating material and supporting windings, the combination with a guide element to be inserted in the slots; of means guided by said guide element for cutting the lining material at the edges of said slots; and means also guided by the guide element for inserting a retainer strip between the turned down edges of the sheared lining material and the edges of the slots.
23. In a device for assembling armatures having an open slotted core lined with insulating material and supporting windings, the combination with a guide element to be inserted in the slots and adapted to press the windings against the bottom portions of the slots; of means guided by said guide element for cutting the lining material at the edges of said slots; and means guided by said guide element for turning down the sheared edges of the lining material against the windings in the slots.
24. In a device for assembling armatures having an open slotted core lined with insulating material and supporting windings, the combination with a guide element to be inserted in the slots and adapted to force the windings against a slot wall, of means guided by said guide element for shearing the lining material at the edges of said slots; and means guided by said guide element for inserting a retainer strip in the slots between the winding and the edges of said slots.
25. In a device for assembling armatures having an open slotted core lined with insulating material and supporting windings, the combination with a guide element to be inserted in the slots and adapted to compact the windings; of means guided by said guide element for shearing the lining material adjacent the edges of said slots; means guided by said guide element for turning down the sheared edges of the lining material against the windings in the slots; and means guided by said guide element for inserting a retainer strip in the slots between the windings and the edges of said slots.
26. In a device for assembling armatures having an open slotted core lined with insulating material and supporting windings, the combination with a guide element to be inserted in the slots; of means for shearing the lining material at the edges of said slots; means guided by the guide element for turning the sheared edges of the lining
- material down against the windings in the slots; and means also guided by the guiding element for inserting a retainer strip in the slots between the turned down edges of the lining material and the edges of the slots.
27. In a device for assembling armatures having an open slotted core lined with insulating material and supporting windings, the combination with a guide element to be inserted in the slots; of means guided by said guide element for turning down the sheared edges of the lining material against the windings in the slots; and means also guided by the guide element for inserting a retainer strip between the turned down edges of the sheared lining material and the edges of the slots.
28. In a device for assembling armatures having cores provided with bottle shaped slots comprising a large winding retaining portion and a restricted neck portion, said core being wrapped with and said slots being lined with a strip of insulation material, the combination with a pilot having flange and web portions adapted to enter retaining neck portions of the slots respectively; of a knife carried by the pilot and adapted to shear the lining material in the slots and so arranged as to be inserted beneath the lining material around the core previous to the insertion of the pilot member into the slots.
29. In a device for assembling armatures having bottle shaped slots with a large winding retaining portion and a restricted neck portion lined with insulating material extending outside the slots; the combination with a pilot having flange and web portions, the flange being adapted to enter the large winding retaining portion of the slot to force the windings down into the slot, the web portion being adapted to enter the restricted neck portion of the slot to act as a guide and to force the lining material therein against the sides of the said restricted neck portion; of a knife carried by the pilot and adapted to cam the lining material toward the web portion of the pilot and cut it off.
30. In a device for assembling armatures having cores provided with bottle shaped slots comprising a large winding retaining portion and a restricted neck portion, said core being wrapped with and said slots being lined with a strip of insulating material; the combination with a pilot having flange and web portions adapted to enter the retaining and neck portions of the slots respectively, of a knife having an angular cutting portion and a body portion and adapted to be inserted in a slot in the web portion of the pilot, the apex of said cutting portion being adjacent the forward extremity of said slot, while the body portion

is rigidly held in position by means of a screw provided in the pilot, thereby tending to hold said knife in a correctly alined position relative to the pilot, for facilitating 5 the shearing of the lining material.

31. In a device for assembling armatures having cores provided with bottle shaped slots comprising a large winding retaining portion and a restricted neck portion, said 10 core being wrapped with and said slots being lined with a strip of insulating material; of a pilot having flange and web portions adapted to enter the retaining and neck portion of the slots respectively; and 15 a retainer strip receptacle formed in the pilot by cutting away a part of the flange portion of said pilot, and adapted to insert a retainer strip between the windings in the retaining portion of the slots and the 20 neck portions thereof, for the purpose of holding said windings in the slots.

32. In a device for assembling armatures having cores provided with bottle shaped slots comprising a large winding retaining portion and a restricted neck portion, said 25 core being wrapped with and said slots being lined with a strip of insulating material; of a pilot having flange and web portions adapted to enter the retaining and neck 30 portions of the slots respectively; and a retainer strip receptacle formed in the pilot in direct alinement with the flange portion thereof, said receptacle being adapted to contain a retainer strip slightly wider than 35 the said flange portion, and capable of being inserted in the armature slots directly in the path of the said flange portion of the pilot to hold the windings in position in the 40 slots.

33. In a device for assembling armatures having cores provided with bottle shaped slots lined with insulating material and containing windings; the combination with a pilot member including means for forcing 45 the windings down into the slots, cutting means for shearing the lining material in the slots; means for folding said sheared paper down against the windings, and means for inserting a retainer strip in said slots; 50 of a magazine formed in a continuation of the pilot member and adapted to contain a plurality of retainer strips; and means for shifting one of these retainer strips from the magazine and inserting said strip in the armatures slots; in determined sequence of operation. 55

34. In a device for assembling armatures having cores provided with bottle shaped slots lined with insulating material and containing windings; the combination with a 60 pilot member including means for forcing the windings down into the slots, cutting means for shearing the lining material in the slots; means for folding said sheared paper down against the windings, and means 65 for inserting a retainer strip in said slots;

of a magazine formed in a continuation of the pilot member and adapted to contain a plurality of retainer strips; a stationary housing in which the pilot member is adapted to move longitudinally; a resilient element connecting the housing and pilot and adapted to hold each in relatively normal position and means associated with the pilot for picking up one of the retainer strips in the magazine and causing it to be placed in 70 position in the receptacle formed in the pilot, for inserting the strip in the armature slots. 75

35. In a device for assembling armatures having cores provided with bottle shaped slots lined with insulating material and containing windings; the combination with a pilot including shearing, paper turning and retainer strip inserting devices; a magazine capable of being inserted and held in a 80 pocket formed in an extension of the pilot, said magazine being adapted to carry a supply of retainer strips; a housing in which the pilot is adapted to move longitudinally, said housing being provided with a hollow 85 handle portion, while the opposite end is provided with buffer edges adapted to engage with the edge of the commutator core when a retainer strip is being inserted; a receptacle formed in the housing and into 90 which a retainer strip is adapted to be inserted when the magazine and housing are in relatively abnormal position; a latch element positioned in the pilot and adapted to slide over the retainer strip until the pilot and housing elements are in relatively normal position when said latch drops behind the retainer strip to hold it in position in a receptacle formed in the pilot member; and 95 a resilient element connected between the pilot and housing elements to bring these two elements into normal relative position when one slot of the armature is completely assembled, and thereby adjust the device for 100 the next assembly operation. 105

36. In a device for assembling armatures having open slotted cores containing windings, the combination with a pilot adapted to insert a retainer strip in the slots; of a magazine retainer strip container associated with said pilot and held in position therein by means of spring controlled latches, and adapted to automatically supply a retainer strip for each cycle of operation of the pilot. 115

37. In a device for assembling armatures having open slotted cores containing windings, the combination with a pilot adapted to insert a retainer strip in the slots; of a magazine retainer strip container associated with the pilot, said magazine having resilient means for causing a retainer strip to be brought into position capable of being inserted in the armature slot at each forward movement of the pilot. 120 125

38. In a device for assembling armatures having open slotted cores containing windings, the combination with a pilot adapted to insert a retainer strip in the slots; of a magazine retainer strip container associated with the pilot and adapted to contain a plurality of retainer strips to be inserted in the armature slots; of a plate in said magazine adapted to force the retainer strips in a downwardly direction through the influence of resilient elements when said magazine is in position in the pilot, and adjustable means for holding said plate in position against the top of the magazine for overcoming the effect of the resilient elements 15 associated therewith, to facilitate the loading of the magazine with retainer strips.
